(57) **CLAIM**

The ornamental design for a remote control target changer (portable) as shown and described.

DESCRIPTION

FIG. 1 is a top, front, left side perspective view of a remote control target changer (portable), showing our new design; FIG. 2 is a top, rear, left side perspective view thereof in a folded state;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof; and,

FIG. 8 is a bottom plan view thereof.

The broken lines in the drawings show portions of the remote control target changer (portable) that form no part of the claimed design.
